UNITED STATES PATENT OFFICE.

EDGAR E. BROSIUS, OF PITTSBURGH, PENNSYLVANIA.

AUTOMATIC REPLAY AND RECORD SHIFT FOR PHONOGRAHS.

Application filed May 7, 1920. Serial No. 379,527.

To all whom it may concern:

Be it known that I, EDGAR E. BROSIUS, a citizen of the United States, residing at Pittsburgh, Allegheny County, Pennsylvania, have invented a new and useful improvement in Automatic Replay and Record Shifts for Phonographs, of which the following is a full, clear, and exact description.

The present invention relates broadly to phonographs, and more particularly to the type employing disk records.

The principal object of the present invention is to provide means adapted to be attached to phonographs of standard construction enabling a single record to be replayed any desired number of times, or permitting the automatic shifting of records after a single playing thereof.

A further object of the present invention is to provide an automatic replay for phonographs comprising mechanical means for lifting the sound box from the record, transferring the same to the starting position, and then gradually lowering the sound box into engagement with the record.

A still further object of the present invention is to provide electrically operated means for controlling the lowering of the sound box onto the record, the electrically operated means being energized at desired intervals which may be timed to permit the change of records or to automatically replay the same record as soon as the sound box is in position.

Another object of the present invention is to provide a mechanically driven record shifting arm, the rotation of which is controlled by means of a friction clutch electrically operated at predetermined times.

Still another object of the present invention is to provide a phonograph with two additional tables, one serving as a source of supply for unplayed records; and the other serving as a source of storage for played records, with means for automatically shifting the records as required; the shifting means being electrically controlled and mechanically operated for synchronizing the shifting of the records with the operation of the phonograph.

An additional object of the present invention is to provide means for readily chang-

ing the device from an automatic replay for an individual record to an automatic playing and record shifting device.

The foregoing and other objects, together with their attendant advantages will be apparent as the invention becomes better understood, by reference to the accompanying specification and drawings forming a part thereof, it being premised that changes may be made in the various details and the manner of operation, within the scope of the appended claims, without departing from the spirit of the invention.

Figure 1 is a plan view of a phonograph having my invention applied thereto.

Figure 2 is a plan view of a portion of the sound box shifting device removed from the phonograph.

Figure 3 is a side view of the mechanism illustrated in Figure 2 showing the same applied to a phonograph.

Figure 4 is a side view of a portion of the shifting device and the electrical controlling means therefor.

Figure 5 is a side view corresponding to Figure 4, showing the sound box in its elevated position.

Figure 6 is a longitudinal sectional view through the electrical control for the sound box.

Figure 7 is a sectional view on the line VII—VII of Figure 6.

Figure 8 is an end view of the structure shown in Figure 6.

Figure 9 is a plan view of the switch for transforming the device from an automatic replay to a combined replay and record shift.

Figure 10 is a side view of the opposite side of the control shown in Figure 6.

Figure 11 is a sectional view of the switch for the replay control, on the line XI—XI of Figure 10.

Figure 12 is a plan view of a portion of the record shifting mechanism.

Figure 13 is a sectional view on the line XIII—XIII of Figure 12.

Figure 14 is an enlarged detail view of a portion of the mechanism illustrated in Figure 12.

Figure 15 is a side view of the mechanism illustrated in Figure 14.

Figures 16, 17, 18, 19 and 20 are diagrammatic views illustrating the electrical connections.

Figure 21 is a side elevation of a modified form of record shifting device.

Figure 22 is a plan view partly in section of a portion of the structure shown in Figure 21.

Figure 23 is a detail plan view of the record shifting magnet.

Figure 24 is a vertical sectional view through the record shifting mechanism.

Figure 25 is an enlarged detail view of the trip for the record shifting magnet, and Figure 26 is a wiring diagram of the connections employed with the modified form of apparatus.

In my Patent No. 1,266,767 of May 21, 1918, there is disclosed mechanism for automatically shifting records for phonographs.

The present invention relates broadly to improvements on the construction disclosed in this patent and combines therewith a replay which is controlled by electric replay magnets, the circuit of which may be controlled to vary the operation of the device.

Referring more particularly to Figure 1 of the drawings, there is illustrated a portion 1 of the body of the support for the phonograph which may be of the cabinet or other well-known type carrying the usual record table 2 and swinging tone-arm 3. These features may be of any usual well known construction and constitute no part of the present invention except as they co-operate with the mechanism provided for automatically replaying or shifting records. Secured to one corner of the support 1 is a bracket comprising an arm 4 carrying a table 5 for the reception of played records, and a second bracket 6 carrying a table 7 upon which may be placed a series of unplayed records. Extending vertically through the center of the attachment is a shaft, referred to in detail hereinafter, carrying a record shifting arm 8 adapted to be driven by the shaft and provided on its outer end with means for engaging a record and carrying it, after it has been played, from the record table 2 to the table 5 where it is automatically dropped. The arm 8 then continues its travel in the direction of the arrow A to the table 7, where it picks up an unplayed record from the supply thereon provided and carries the same to the record table 2. It will be apparent that the usual tempo control and brake control for the record table may be provided, as indicated in the drawings.

Replay device.—It is necessary, in order to replay records, to provide means for shifting the sound box and stylus automatically from the inner sound groove of the record to the outer or starting groove, and this mechanism, in the present instance, has been termed a "replay" device. The mechanism

is illustrated as an attachment for standard machines; more particularly in Figures 2 and 3 as comprising a cam 9 secured to the mandrel 10 provided for driving the record table 2. This cam extends around the major portion of the mandrel and is provided with a surface *a* gradually inclined to constitute a lifting device; a surface *b* sharply inclined to permit a rapid descent of the sound box toward the record, and a third surface *c*

gradually inclined so that during the last portion of the travel of the sound box it will be lowered without jar into engagement with the record. Between the ends of the surfaces *a* and *c* there is provided an opening

11 through which one end of the arm for accomplishing the transfer of the sound box is adapted to pass. This arm is generally U-shaped and comprises a leg 12 journaled adjacent its opposite ends in a bracket 13 which

is adapted to be secured to the support 1 below the record table and extend radially outward from the mandrel 10. The inner end of the leg 12 is bent downwardly in the form of a crank 14, which crank is in turn

provided with a pin or roller 15 adapted to engage, at desired intervals, the cam 9. Normally, the pin or roller 15 lies below the body of the cam, as clearly indicated in Figure 3 of the drawings. The other leg 16 is

provided with a sliding sleeve 17 carrying at one end an adjustable stop 19 adapted to be engaged by a suitable projection 20 formed on the sound box 20', this engagement occurring when the stylus has finished playing the record. The sleeve 17 is also pro-

vided with a second stop 22 adapted to engage the sound box 20' in a position where it may be vertically lowered into engagement with the outer groove of a sound record. It

will be apparent that this stop may also be adjustable to permit the device to be used with standard records of different dimensions. The legs 12 and 16 are connected by a yoke

23 which extends through the mechanism controlled by the replay magnets. In Figure 3, in full lines, the projection 20 is il-

lustrated as being in engagement with the stop 19, while in dotted lines the sound box 20' is illustrated as in engagement with the stop 22.

The leg 16 is normally held in the full line position illustrated in Figures 1, 2 and 3, and is moved from this position to effect transfer of the sound box when the projec-

tion 20 engages the stop 19, through mechanism now to be described in detail.

Referring particularly to Figures 6, 7 and 11, it will be noted that the legs 12 and 16, which legs are connected by the yoke 23, extend through mechanism controlled by replay magnets 24. These replay magnets are

mounted in a frame 25 which carries a bearing 26 for the leg 12. Pivotedly secured to the bearing 26 is a holding lever 27 extend-

70

ing forwardly toward the magnets 24 and having its free end engaged by a catch 28 having a pivotal mounting 29 on the frame 25 and normally held in engagement with the holding lever 27 by a spring 30, the extent of movement of the catch 28 being controlled by a tail 31 which engages the frame 25, when the catch is in engagement with the holding lever. Also carried by the bearing 26 is a leaf spring 32 bearing against the underside of the holding lever 27 and tending at all times to elevate the same. The catch 28 is provided with an angular projection 33 in back of which extends a projection 34 on the sleeve 17 on the leg 16. When the projection 20 engages the stop 19, the continued travel of the stylus in the record groove will slide the sleeve 17 inwardly, thereby causing the projection 34 to engage the projection 36 and draw the catch 28, against the action of the spring 30, out of engagement with the holding lever 27. The spring 32 will now be free to lift the holding lever 27, which will in turn lift the leg 16 which overlies the same. This movement will be enough to cause the pin or roller 15 to pass vertically through the slot 11 in the cam 9 whereupon rotation of the mandrel 10 will cause the same to be engaged by the cam 9. During the travel of the pin 15 over the cam surface *a* the leg 16 will be moved from its full line position shown in Figures 1, 2, 3 and 6 to the dotted line position shown in these figures, thereby engaging the sound box and lifting the same from engagement with the record. The inclination of the leg 16 will be sufficient, as clearly illustrated, to cause the sound box to slide by gravity along the sleeve 17 into engagement with the stop 22. Engagement with the stop will check the movement of the sound box and at the same time slide the sleeve 17 inwardly, so that upon descent of the leg 16 the projection 34 will be in the proper position to pass behind the angular projection 33. During the travel of the pin or roller 15 on the cam surface *b* the weight of the sound box will be sufficient to cause a comparatively rapid descent or lowering of the leg 16. When the pin or roller 15 engages the surface *c*, the rapidity of the lowering movement will be checked, and when the pin 15 finally leaves the cam surface *c*, the stylus will have been gently lowered into engagement with the record.

For resetting the parts after each operation of the replay device, the leg 16 is provided with a pivoted lever 35, which, in traveling from its full line position shown in Figure 6 to the dotted line position shown therein will force the lever 27 downwardly against the action of the leaf spring 32 so that the catch 28 may engage the same automatically and hold it in its original position. The nose 36 of the catch 28 is inclined, as

clearly shown in Figure 7, to permit the resetting of the holding lever 27, as will be apparent.

The foregoing operations will occur with the mechanism described upon the completion of the playing of each record, as long as the phonograph is in operation, unless some means is provided for holding the leg 16 and the sound box 20' in their elevated positions with the stylus out of engagement with the record. In the present case I have provided mechanism for holding the parts in this inoperative position, and this mechanism will now be described.

Pivoted carried by the leg 16 is a lever 37 normally extending forwardly between the replay magnets 24 and supported on the cross bar 38' to be described in detail hereinafter. This lever is provided on its lower surface intermediate the ends thereof with a detent 39 adapted, when the lever is in the dotted line position shown in Figure 6, to engage and hook over the cross bar 38'. This lever automatically drops into this position as the arm 16 is raised, and thereby holds the arm 16 in the elevated position until released.

In the present case, I have provided electrically controlled means for disengaging the lever 37 from the cross bar 38' to permit lowering of the sound box. This means comprises the replay magnets 24 which are formed with hollow cores adapted to receive the core members or armatures 40 carried by the transversely extending bar 41. The bar 41 carries an upstanding lug 42 which, in the normal position of the parts of the replay device during playing of a record, underlies the free end of the lever 37 out of engagement therewith. When the parts are in their elevated, inoperative, position, the free end of the lever 37 immediately overlies the lug 42 so that when the circuit of the replay magnets 24 is energized to lift the core pieces or armatures 40 and the transverse bar 41 connecting the same, the lug 42 will engage the underside of the lever 37 and lift the same out of engagement with the cross bar 38', thereby permitting the parts to gravitate to their operative positions. During the period that the parts are in their inoperative elevated positions, the pin or roller 15 occupies such a position relative to the highest portion of the cam 9 that it is engaged thereby during each revolution of the table mandrel. This results in a movement of the leg 16 from the dot and dash center line *d* to the dot and dash center line *e* shown in Figure 6, this movement being sufficient to disengage the detent 39 from the cross bar 38' a sufficient extent to permit the lug 42 to function in the manner described.

When the device is used merely for replaying records, it is desirable that means

1
be provided for preventing the engagement of the detent 39 with the transverse bar 38. For this purpose I mount a second transverse bar 38 on a lever 43 having a pivotal 5 mounting 44 on the frame 25. When the lever 43 is in its full line position shown in Figure 7, the bar 38 is lowered to such an extent that the cross-bar 38' will be engaged by the detent 39 while, if the lever 43 is in its dotted line position, this engagement will not occur. It will be apparent, therefore, that the action of the device may be easily changed by shifting the position of the lever 43.

15 In actual practice, it has been found desirable to provide the frame 25 with a leaf spring 45 which may be conveniently mounted on the bearing 26 so as to engage a stop 45^a on the lever 37 as the lever rises from its 20 lower to its upper position under the influence of the leg 16. Due to the provision of this spring, when the detent 39 is disengaged from the bar 38, the spring will assist the gravity action and insure the lowering of 25 the sound box.

The foregoing replay device, as described and illustrated, is operative by itself with the mechanism described. It has been found, however, that the replay is particularly adapted for use in connection with an automatic record shift due to the provision of means for holding the sound box in its elevated position for predetermined periods of time. The construction and operation of 30 35 the automatic record shift with relation to the replay device will now be described.

Automatic record shift.—Broadly, the record-shifting device comprises an arm adapted to be operated automatically at predetermined times to pick up a record from the record table after it has been played, transfer the same to a desired point, pick up a new record, and place it on the record table in place of the record previously removed therefrom. This arm 8, before described, is provided with a hub portion 46 carrying an adjustable bearing 47 co-operating with the upper end of a shaft 48. The hub 46 is held in central position about the shaft by means of a lower or intermediate bearing 49, clearly illustrated in Figure 13. For rotating the shaft 48 it may be extended through the support 1, in a suitable bearing 50 and provided on its lower end with 55 any desired type of gearing 51 adapted to be driven from the mandrel 10 through a transverse shaft 52 and gearing 53. It will be apparent from the nature of the gearing provided that the shaft 48 is rotated continuously during the rotation of the record table. The arm 8 is not adapted, however, during the entire operation of the record table to swing continuously, and for this reason there is provided a clutch enabling a 60 65 driving connection to be established at will

between the shaft 48 and the hub 46. As illustrated, this connection may comprise a solenoid 54 carried by the hub 46, and provided with a core 55 having its inner end roughened or serrated to engage a similar 70 surface 56 on the shaft 48. When the solenoid 54 is energized to draw the core 55 to its inner position, the parts will be frictionally clutched together and driven in unison, but upon deenergization of the solenoid this 75 driving connection will be destroyed.

For controlling the circuit of the solenoid, the hub 46 may be provided with a plurality of slip rings, illustrated as four in number, and bearing the reference characters 57 to 60, inclusive. These slip rings constitute a portion of an electric circuit, illustrated for sake of clearness diagrammatically in Figures 16 to 20.

Referring particularly to Figure 16, there are illustrated two line wires 61 and 62, respectively. The line wire 62 leads from any desired source of current through a safety fuse 63 to a brush 64 in engagement with the periphery of the slip ring 60. This ring has 85 an electrical connection 65 with the slip ring 57 which, in turn, has an electrical connection 66 with the frame 67 of a make and break device mounted on the arm 8. This make and break device, as clearly illustrated 90 in Figures 14 and 15, comprises a movable member 69 pivotally connected to the frame 67 and carrying a contact 70 adapted to co-operate when the make and break device is in closed position, with a second contact 71 100 insulated from the frame 67. This contact 71 has a connection 72 with the solenoid 54, and the opposite side of the solenoid is connected through a wire 73 with the ring 58. Co-operating with the ring 58 is a brush 74 105 having a connection 75 with the binding post 76 on the frame of the replay magnets 24. From the binding post 76 the current passes through the frame 25 to the connecting bar 41 for the solenoid core pieces 40, thence to the opposite side of the frame 25 to the binding post 77. This portion of the frame 25 is insulated by means of hard rubber, fibre or the like 78, from the remainder 110 of the frame so that the circuit can only be completed through the bar 41 when in its lower position in engagement with the frame portions described. The terminal 77 has a connection 78^a with one side of a switch contact 79, the opposite contact 80 of which has 115 a connection 81, with one contact 82 of a manual switch controlled by the lever 43 of the replay device. From the contact 82 the current is adapted to pass when the switch is closed through the switch blade 83 to the wire 61. From the foregoing it will be apparent that when the contacts 79 and 80 are bridged and the switch blade 83 is in its closed position in engagement with the contact 82, current will flow from the line 120

wires 61 and 62 through the solenoid 54 for energizing the same and forcing the armature 55 into engagement with the shaft 48 causing rotation of the arm 8. Normally, 5 however, the contacts 79 and 80 are not connected by a switch, this condition being shown in Figure 16, so that the arm 8 during the playing of a record is permitted to extend over the record table, as shown in 10 Figures 12 and 13.

Upon completing the playing of a record, the elevation of the leg 16 is adapted to connect the contacts 79 and 80 by means of a suitable switch mounted in the frame 25 of 15 the replay device. Referring again particularly to Figure 6, the lever 37 is illustrated as provided with pins 84 extending beyond the opposite sides thereof. During the time that the lever 37 moves from its full line 20 position illustrated in this figure to its dotted line position, these pins will drop over and straddle the tail 85 of the switch blade 86 pivotally mounted at 87 to the frame 25 of the replay device. Continued 25 movement of the lever 37 will be effective for moving the switch 86 from its full line position to its dotted line position, thereby closing the circuit through the contacts 79 and 80 and energizing the solenoid 54 in the 30 manner described.

During the movement of the leg 16 from its lower to its upper positions, a pin or projection 88 on the yoke 23 engages a pivoted member 89 secured to the arm 90 and draws 35 the same to the left, as viewed in Figure 10, against the action of a spring 91. This operation forces a plunger 92 inwardly within a dash pot cylinder 93, movement in this direction being permitted by the opening of 40 a flap valve 94 in the base of the plunger 92. The arm 90 carries a pivoted contact blade 95 adapted normally to engage the contacts 96 and 97, as shown in Figure 10. Once this 45 circuit is broken, however, the time element, comprising the dash pot mechanism described, will prevent immediate closing of the circuit.

This circuit, referring again to Figure 16, 50 may be traced from the line wire 62 to the contact 70, as before described, and thence to the contact 71 and through the wire 98 to the disk 59. This disk is provided with a projection 99 adapted to engage a wiper or brush contact 100 having a connection 101 55 with the contact 96 from which the current flows through the blade 95 to the contact 97 and wire 102 to one of the replay magnets 24. These magnets are connected in series, as shown, and the opposite terminal of the 60 other replay magnet is connected to the contact 79. When the switch 83 is closed, as before described, current will flow to the line wire 61. From the foregoing, it will be apparent that if the circuit, including the 65 replay magnets 24, were energized at the same

time that the solenoid 54 is energized, the replay magnets 24 would be effective, through the lug 42, to lower the leg 16, thereby dropping the sound box before shifting of the records occurs. The provision of the time element prevents this operation, however, by opening the circuit between the contacts 96 and 97 for a sufficient period of time to permit the projection 99 to pass out of contact with the brush 100 due 70 to the rotation of the arm 8. When the time element resumes its original position, the circuit between 99 and 100 will be broken and the replay magnets will not thereafter be energized until a complete revolution of the 80 arm 8 has occurred and the contacts 99 and 100 again brought together. This complete revolution will be sufficient to remove the played record and supply an unplayed record, after which time it will be desirable to 85 lower the sound box.

The diagram in Figure 16 illustrates the circuit connections during the playing of a record. The diagram in Figure 17 illustrates the circuit connections as they are at 90 the time a record has been played and the arm 16 is in its elevated position, the time element in this diagram being illustrated as in its open position, as shown in elevation in Figure 5.

Carried by the outer end of the arm 8 is a fixed solenoid 103 provided with a core 104 fixed to the arm 8 and extending longitudinally through the open center of the 100 solenoid. Co-operating with the solenoid 103 is a second solenoid 105 connected in parallel to the first solenoid and provided with a projecting core 106 adapted to slide vertically around the core 104 and into the open space of the first solenoid, when the 105 solenoids are energized. The lower portion of the core 106 of the solenoid 105 is formed with a pocket 107 adapted to lie over the projecting end of the mandrel 10 during the 110 playing of a record. For preventing rotation of the solenoid 105, the arm 8 is provided with a finger 108 to the lower end of which is secured a guide rod or wire 109 connected at its outer end at any desired point to the solenoid. After the record on the 115 record table has been played, as described, and at the same time that the solenoid 54 has been energized for establishing a driving connection between the shaft 48 and the arm 8, the solenoids 103 and 105 are energized to lift the played record from the table. The pin or core 104 projects downwardly far enough so that when the solenoid 105 is 120 lifted to its dotted line position, the record will be properly centered. The circuit connections at this time are clearly shown in Figures 16 and 17. The current will flow from the wire 62 to the disk 57, thence to the contact 71 through the connections provided, and from this contact through the 125 130

wire 110 to the solenoids 103 and 105, respectively, the opposite sides of the solenoids being connected by the wire 111 to the ring 58. From the ring 58 the circuit is completed through the replay device, as before described.

It will thus be apparent that as the arm 8 starts to rotate in the direction of the arrow A, it will lift the record from the record table and carry the same as long as the solenoids 103 and 105 are energized. For breaking the circuit to these solenoids, and at the same time breaking the circuit through the solenoid 54, there is provided a support 112 partially surrounding the hub 46 and provided with an adjustable stop 113, clearly shown in Figure 14. As the arm 8 rotates to its position above the table 5, the pawl 114 pivotally mounted on the free end of the bell crank lever 115 which is, in turn, provided with a pivotal bearing 116 on the hub 46, will engage the stop 113 and swing the bell crank lever against the action of the spring 117 into dotted line position shown in Figure 15. This will, in turn, swing the lever 118 about its pivot 119 to the dotted line position shown in this figure, the pivoted end 120 of the lever during this period of its travel passing freely over the projecting end of the pivoted portion 69 of the make and break device. As soon as the pawl 114 passes out of engagement with the stop 113, the parts will move to their original position. During this movement, however, the pivoted end 120 of the lever 118 will engage the free end of the member 69 and separate the contacts 70 and 71, thereby breaking the circuit to the solenoids 54, 103 and 105, simultaneously, causing the record 40 to be dropped, and breaking the driving connection between the shaft 48 and the arm 8. As soon as the record is dropped, the momentum of the arm 8 will carry it away from the record so that when the circuits are re-established the record will not be again lifted from the table 5 for the played records. It will be apparent that by making the stop 113 adjustable, the exact point of dropping the played record may be controlled. Connected to the members 67 and 69 of the circuit making and breaking device is a cylinder 121 and a plunger 122, respectively, constituting a second time element corresponding to the time element before described.

55 This time element is provided to hold the contacts 70 and 71 separated a sufficient time to permit the momentum of the arm 8 to carry the lifting solenoids for the record out of engagement with the record, as described. This time element is only operative for holding the contacts separated a comparatively short time, and during the travel of the arm from the table 5 to the table 7, the circuits will be re-established.

60 65 Just prior, however, to the time that the arm

reaches the storage table 7 for the new records, the pawl 114 will engage a second stop 123 similar to the stop 133, and the operation just described will be repeated, permitting the solenoid 105 to drop into engagement with the new record over the centering pin 124 which insures the correct positioning of the record. The time element for the circuit make and break device will again permit closing of the circuits and the new record will be lifted from the table 7 and carried to the record table 2. Just prior to the time that the arm reaches the center of the record table 2 the pawl 114 will again engage an adjustable stop 123^a, causing the record to be dropped onto the table and the solenoid 105 to be centered over the upper portion of the mandrel 10, as shown in Figure 13. At this time, the contact 99 will engage the brush 100, thereby closing the circuit to the replay magnets 24, energizing the same and causing them to raise the lug 42 to release the lever 37 and lower the sound box onto the new record.

In Figure 18 the circuit connections are shown as they are at the time the played record is dropped onto the table 5, the contacts 70 and 71 being shown as separated. In Figure 19 the circuit connections are shown as they are at the time the arm reaches the table 7 for the new records, the contacts 70 and 71 also being open in this figure to permit the solenoid 105 to drop into engagement with a new record; and the contact 99 illustrated as having traveled substantially two-thirds of a rotation, this amount depending upon the exact positioning of the tables 5 and 7, as will be apparent. In Figure 20 the circuit connections are illustrated as they are at the time the arm drops the new record onto the record table, the contacts 99 and 100 being shown in engagement, and the next change in the circuits will take place upon the lowering of the leg 16 resulting in moving the switch 86 from between the contacts 79 and 80, thereby re-establishing the conditions shown in Figure 16.

It will, of course, be obvious that all of the records utilized in connection with this apparatus must be provided with a central magnetic portion as clearly shown in my prior patent before referred to. The table 7 may be provided with a spring 125' adapted to always hold the top record of the unplayed pile in proper position. With the form of my invention described, the power of the driving motor for the phonograph is utilized through the cam 9 for raising the sound box, thereby obviating the necessity of employing separate lifting means for this purpose. Once having been raised from the record, the lowering of the sound box is controlled by the electrical means described. The switch 83 being operated by the lever

43, it will be apparent that when the lever 43 is moved from one position to the other to change the device from an automatic replaying device to a combined replaying and record-shifting device, the switch 83 will be automatically thrown to the proper position, and vice versa.

In Figures 21 to 26, both inclusive, there is illustrated a slightly modified arrangement which, in some instances, may be desirable in place of the mechanism just described, due to the elimination of the time elements of the character shown. In these figures parts corresponding to the parts already described are indicated by the same reference characters with the letter *a* affixed thereto. In Figure 21, the arm 8^a is indicated as provided at its outer end with the solenoids 103^a and 105^a, these solenoids in this form of my device being prevented from rotational movement by a guide rod 125 secured at its lower end to the spool for the solenoid 105^a, and having its intermediate portion passing through the spool flanges for both of the solenoids.

The upper end of the guide rod 125 is formed with a slot 126 adapted to receive one end of the lever 127 having a pivotal mounting 128, and having its inner end bifurcated to straddle the core 129 extending longitudinally through the solenoids. Secured in the bifurcated portion of the lever 127 and extending through the core 129 is a pin 130. The intermediate portion of the guide rod 125 may be provided with an adjustable stop 131. By reason of this construction, when the solenoid 105^a moves to its lower position, the guide rod 125 will be pulled downwardly, thereby elevating the core 129 for the purpose to be described hereinafter.

Extending longitudinally through the core 129 is a rod 132 having its lower end in engagement with one end of the bell crank lever 133 pivotally mounted at 134 in a slotted portion of the core 129, and having its opposite end projecting downwardly below the end of the core. When the arm 8^a, carrying a new record from the supply table 7, reaches the position over the mandrel 10^a for the record table 2^a, the lower portion of the pawl 133 will engage the upper end of the mandrel and lift the rod 132. The upper end of this rod 132 underlies a spring contact 135 secured at one end to the support 137 on the core 129 and adapted to be pushed upwardly by the rod 132 into engagement with the contacts 136 for establishing electrical connection between these contacts. The hub portion 46^a of the arm 8^a surrounds the shaft 48^a in a manner similar to that already described in connection with the preceding form of my invention, and carries two rings 138 and 139 respectively, taking the place of the

four slip rings 57 to 60. The side of the hub 46^a also carries a solenoid 54^a provided with a core 55^a adapted to form a driving connection between the shaft 48^a and the arm 8^a. In this form of my invention, the upper end of the shaft 48^a has an extension 140 carrying a roller 141 in engagement with the core 142 of the solenoid 143. The opposite end of the core 142 is provided with a contact or switch member 144 adapted to co-operate with the two contacts 145. The free end of the core 142 projecting beyond the roller 141 is formed with a hook 146 adapted to engage the upper end of a lever 147 having a pivotal mounting 148 on the hub 46^a of the record shifting arm. The lower end of the lever 147 carries a circuit making or switch member 149 adapted to co-operate with the fixed contacts 150 secured to and projecting upwardly from the support or cabinet 1^a.

With this mechanism, and referring more particularly to Figure 26, the operation will be as follows, assuming the switch 83^a to be in its closed position.

The rod 132 having been raised to close the contacts 137, current will flow through the line wire 62^a and safety fuse 63^a to the wire 151 in electrical connection with the brush 152 co-operating with the ring 139. From this ring the current will flow through the wire 153 to the contacts 137 and thence through the wire 154 to the solenoid 143 thereby energizing the same and causing the core 142 to be moved to the left, as viewed in Figures 21 and 22, against the action of the friction roller 141. This will break the electrical connection between the contacts 145. From the solenoid 143 the current will flow through the wire 155 to the ring 138 and thence through the brush 156 and wire 157 to the contact 79^a. From this contact the current will flow through the switch member 86^a of the replay device to the contact 80^a and thence through the wire 158 and switch 83^a to line wire 61^a. Opening the contacts 145 will break the circuit through the solenoids 54^a, 103^a and 105^a, respectively, thereby causing the record to be dropped on a record table in playing position. The dropping of the solenoid 105^a will, however, result in lifting the core 129, as before pointed out, thereby enabling the pawl 133 to pass from its dotted line position shown in Figure 25 to the full line position shown in this figure, which will result in again lowering the rod 129 and opening the electrical connection between the contacts 137. The friction roller 141 will now be effective for slowly advancing the core 142 to its original position to establish electrical connection between the contacts 145. During this travel the hook 146 thereon will engage the lever 147 and

move the same from the dotted line position shown in Figure 21 to the full line position shown therein against the action of the spring 159, and establish electrical connection between the contacts 150. Current will now flow from the line wire 62^a through the safety fuse 63^a and wire 160 to one of the contacts 150; thence through the member 149 to the other contact which is connected 10 by wire 161 to one side of one of the replay magnets 24^a. The opposite side of the other replay magnet is connected by wire 162 to wire 158 through which the current flows to the line wire 61^a through the switch 83^a. 15 The replay magnets being energized, the sound box will be lowered into engagement with the record through the mechanism already described in detail in connection with the other figures of the drawings.

20 Upon completing the playing of the record, the sound box lifting leg 16 will lift the sound box from the record and through the mechanism provided will draw the switch 86^a between the contacts 79^a and 80^a. 25 In this position current will flow from the line wire 62^a to the ring 139 and from this ring through wire 163 to one side of each of the solenoids 103^a and 105^a. After traversing the solenoids the current will flow 30 through wire 164 to one of the contacts 145 and thence through the member 144 to the other contact 145. The current will flow from the last mentioned contact 145 through the wire 166 to the solenoid 54^a, the opposite side of which is connected by wire 167, to the ring 138. From this ring the circuit will be completed to the line wire 61^a, as described heretofore. These circuits being completed, the played record will be lifted 35 from the record table and transferred, and the regular sequence of operations will take place resulting in the positioning of a new record on the record table.

The advantages of the present invention 40 reside in the provision of means controlled by the driving mechanism for the phonograph for positively lifting the sound box out of engagement with the record, and in the provision of electrically controlled 45 means for controlling the subsequent lowering of the sound box.

Further advantages result from the means 50 provided for conveniently changing the device from a replaying device to a combined 55 replaying and record shifting device.

I claim:

1. In a phonograph, a record table, a reproducer cooperating therewith, a cam, a reproducer lifting arm having a portion 60 adapted to engage said cam and another portion adapted to engage the reproducer, means normally urging said cam engaging portion into engagement with the cam, and means normally rendering said means 65 ineffective, substantially as described.

2. In a phonograph, a record table, a reproducer cooperating therewith, a cam, a U-shaped reproducer lifting arm having a cam engaging portion and a reproducer engaging portion, means normally urging said cam engaging portion into engagement with the cam, and means normally rendering said means 70 ineffective, substantially as described.

3. In a phonograph, a record table, a reproducer cooperating therewith, a cam, a reproducer lifting arm having a cam engaging portion and a reproducer engaging portion, means normally urging said cam engaging portion into engagement with the cam, holding means for normally rendering said 80 means ineffective, and means for releasing said holding means, substantially as described.

4. In a phonograph, a record table, a reproducer cooperating therewith, a cam, a reproducer lifting arm having a cam engaging portion and a reproducer engaging portion, means normally urging said cam engaging portion into engagement with the cam, means 85 normally preventing said means from being effective, and means formed on said reproducer engaging portion for rendering said last named means ineffective after a record has been played, substantially as described.

5. In a phonograph, a record table, means 90 for rotating said table, a reproducer, a reproducer lifting arm, actuating means therefor, means normally preventing said actuating means from moving said lifting arm into lifting engagement with the reproducer, and means effective during a single rotation of said table for lifting said arm into engagement with the reproducer for shifting the same across the record table, substantially 95 as described.

6. In a phonograph, a record table, a mandrel for rotating said table, a reproducer, a reproducer lifting member normally out of engagement with the reproducer, said member comprising diverging legs, and means effective during a single rotation of said table for swinging one of said legs into engagement with the reproducer for lifting the same from the record table and transferring the same thereacross, substantially as described.

7. In a phonograph, a record table, a reproducer, a mandrel for driving said table, a cam driven by said mandrel, a reproducer lifting member having a cam engaging portion and a reproducer engaging portion, and means for supporting said member with the cam engaging portion below the record table and the reproducer engaging portion above the record table, said cam engaging portion 120 being normally out of engagement with said cam and said cam having an opening therethrough to permit the cam engaging portion to move into engagement therewith, substantially as described.

8. In a phonograph, a record table, a mandrel for rotating said table, a reproducer, a reproducer lifting member having portions extending on opposite sides of said table, one 5 of said portions being adapted to engage and lift the reproducer from the table, said portion being normally out of engagement with the reproducer, and means on said mandrel effective during a single rotation of said 10 table for shifting said portion into engagement with the reproducer for transferring the same to starting position, substantially as described.
9. In a phonograph, a record table, means 15 for rotating said table, a reproducer, a reproducer lifting member having a reproducer engaging portion, actuating means for said lifting member, holding means normally preventing said actuating means from 20 moving the lifting member into engagement with the reproducer, means on said lifting portion for releasing said holding means, and means effective during a single rotation of said table for swinging said portion into 25 engagement with the reproducer for lifting the same from the table, substantially as described.
10. In a phonograph, a record table, a reproducer cooperating therewith, a cam concentric with said table and having different 30 portions of its surface extending at different inclinations, a reproducer lifting arm having a portion adapted to engage said cam and another portion adapted to engage 35 the reproducer, means normally urging said cam engaging portion into engagement with the cam, and means normally rendering said means ineffective, substantially as described.
11. In a phonograph, a record table, a reproducer cooperating therewith, a cam concentric with said table and having an operating 40 surface of changing inclination, a U-shaped reproducer lifting arm having a cam engaging portion and a reproducer engaging portion, means normally urging said cam engaging portion into engagement with the cam, and means normally rendering said means ineffective, substantially as described.
12. A replay device for phonographs, comprising a lifting member adapted to engage the reproducer of a phonograph and lift the same from the record table, actuating means for said lifting member, holding means normally preventing said actuating means from 50 moving the lifting member into engagement with the reproducer, means for releasing said holding means to cause the lifting member to engage and lift the reproducer, and means for holding said member and reproducer in elevated position, said last mentioned means being movable to inoperative position at will, substantially as described.
13. A replay device for phonographs, comprising a lifting member adapted to engage the reproducer of a phonograph and lift the 55 same from the record table, actuating means therefor, means normally holding said actuating means to permit said member to remain out of engagement with the reproducer, means for releasing said holding means to permit the member to engage and lift the reproducer, means for lifting said member and reproducer to elevated position, means for holding said member and reproducer in elevated position, and means 60 either manually or automatically operable for releasing said second holding means and lowering the reproducer into engagement with a record, substantially as described.
14. A replay device for phonographs, comprising a reproducer lifting member, a sleeve slidable thereon, a stop on said sleeve adapted to engage the reproducer after a record has been played, means controlled by said stop for swinging said member into engagement with the reproducer for lifting the same from the record and a second stop on said sleeve determining the starting position of said reproducer, substantially as 65 described.
15. In a phonograph, a record table, a reproducer, a cam having an upwardly inclined portion and two downwardly inclined portions, said downwardly inclined portions being of different pitch, a reproducer lifting member having a cam engaging portion and a reproducer engaging portion, actuating means for said lifting member, and means normally preventing said actuating means from moving the cam engaging portion into engagement with said cam, substantially as described.
16. In a phonograph, a record table, a reproducer, a cam having an upwardly inclined portion and two downwardly inclined portions, said downwardly inclined portions being of different pitch, a reproducer lifting member having a cam engaging portion and a reproducer engaging portion, actuating means for said lifting member, means normally preventing said actuating means from moving said cam engaging portion into engagement with said cam, and means for releasing said holding means, substantially as described.
17. In a replay device for phonographs, a reproducer lifting member, means for initially lifting said member, means for bringing said member when so lifted into engagement with the reproducer for lifting the same, means for holding said first mentioned means in inoperative position, means for releasing said holding means to permit the lifting means to operate and cause said second means to engage the lifting member and lift the reproducer, and means for resetting said holding means during such lifting operation, substantially as described.
18. In a replay device for phonographs, a reproducer lifting member having diverg-

- ing legs, means adapted to engage one of said legs for swinging the other of said legs into engagement with the reproducer for lifting the same, normally inoperative means urging said first mentioned leg into engagement with said means, and means on said second mentioned leg for rendering operative said normally inoperative means, substantially as described.
- 10 19. In a replay device for phonographs, a reproducer lifting member adapted to occupy operative and inoperative positions with respect to the reproducer, normally inoperative means urging said member to operative position, and means for rendering operative said normally inoperative means, substantially as described.
- 20 20. In a replay device for phonographs, a reproducer lifting member normally out of engagement with the reproducer, means for swinging said member into engagement with the reproducer for lifting the same, means for holding said member in its elevated position to maintain the reproducer out of engagement with a record, and electrically controlled means for releasing said holding means, substantially as described.
- 25 21. An attachment for phonographs, comprising a replay device, a record shifting device, and a single means operable at will for changing said attachment from a replaying device to a combined replaying and record shifting device, substantially as described.
- 30 22. An attachment for phonographs, comprising a replay device, a record shifting device, said replay device having means for shifting a reproducer from its final to its starting position, a switch operated thereby, means for holding the reproducer in its starting position out of engagement with the record, and means controlled by said switch for removing a played record and bringing a new record into playing position, substantially as described.
- 35 23. An attachment for phonographs, comprising a replay device, a record shifting device, said replay device having means for shifting a reproducer from its final to its starting position, a switch operated thereby, means for holding the reproducer in its starting position out of engagement with the record, and means controlled by said switch for removing a played record and bringing a new record into playing position, and means controlled by said record shifting means for lowering the reproducer into engagement with the new record, substantially as described.
- 40 24. An attachment for phonographs, comprising a replay device, and a record shifting device, normally inoperative means for operating both of said devices from the motor which drives the phonograph, and means controlled by said replay device for establishing an operative driving connec-
- tion between the driving means and said record shifting device, substantially as described.
- 45 25. An attachment for phonographs, comprising a replay device and a record shifting device, normally inoperative means for operating both of said devices from the motor which drives the phonograph, and an electromagnetically operated clutch controlled by said replay device for rendering the driving means for said record shifting device operative, substantially as described. 70
- 50 26. An attachment for phonographs, comprising a replay device, a record shifting device, lifting magnets carried by said record shifting device, and a switch operated by said replay device for energizing said magnets, substantially as described. 75
- 55 27. An attachment for phonographs, comprising a replay device, a record shifting device, said replay device comprising means for lifting the reproducer from the played record, transferring the same to the starting position and holding the same in said position, means operated by said replay device after the reproducer has been lifted from a played record for operating said record shifting device, and means controlled by said record shifting device after a new record has been substituted for the played record for lowering the reproducer into engagement with the new record, substantially as described. 80
- 60 28. An attachment for phonographs, comprising a replay device, a record shifting device, said replay device comprising means for engaging the reproducer, lifting the same from a played record and moving the same to starting position, means for holding the reproducer in starting position out of engagement with the record and means controlled by the record shifting device for releasing said holding means after a new record is in playing position, substantially as described. 85
- 65 29. An attachment for phonographs, comprising a replay device, a record shifting device, normally inoperative means for actuating said record shifting device from the driving motor for the phonograph, and means controlled by said replay device for rendering said connection operative, substantially as described. 90
- 70 30. An attachment for phonographs, comprising a replay device, a record shifting device, said replay device comprising a lifting member, a cam for engaging said member to move the same into engagement with the reproducer to lift the same from a played record, means for holding said member and reproducer in elevated position, an electromagnetic means controlled by the record shifting device for releasing said holding means, substantially as described. 95

31. An attachment for phonographs, comprising means for lifting a reproducer from the played record and transferring the same to starting position, means for holding 5 said reproducer in said starting position, a table for played records, a table for un-played records, means for transferring the played record from the record table to the table for played records and depositing the 10 same, means for driving said means to the table for un-played records and causing the same to pick up an un-played record and to transfer the same to the record table, and means for lowering the reproducer into engagement with the new record, substantially as described. 15
32. An attachment for phonographs, comprising a member for engaging the reproducer and lifting the same from the played 20 record, said member being operative to transfer the reproducer to starting position, means for holding the reproducer in said starting position out of engagement with the record, a record shifting arm, a lifting 25 magnet carried thereby, means for driving said arm, means controlled by said member for energizing said magnet and rendering said driving means operative, means for temporarily de-energizing said magnet after 30 the arm has completed part of a revolution, means for temporarily de-energizing said magnet after the arm has completed another part of a revolution, means for temporarily de-energizing said magnet after the arm has 35 returned to its original position, and means controlled by said arm for lowering the reproducer into engagement with the record after said revolution has been completed, substantially as described. 40
33. An attachment for phonographs, comprising a member for engaging the reproducer and lifting the same from the played record, said member being operative to transfer the reproducer to starting position, 45 means for holding the reproducer in said starting position out of engagement with the record, a record shifting arm, a lifting magnet carried thereby, means for driving said arm, means controlled by said member for energizing said magnet and rendering said driving means operative, means for temporarily de-energizing said magnet after the arm has completed part of a revolution, means for temporarily de-energizing said 50 magnet after the arm has completed another part of a revolution, means for temporarily de-energizing said magnet after the arm has returned to its original position, electro-magnetic means energized by said arm after 55 the arm has completed a revolution for lowering the reproducer into engagement with a record, and a time element in circuit with said electro-magnet, substantially as described. 60
34. An attachment for phonographs, comprising a reproducer lifting member normally out of engagement with the reproducer, means for lifting said member into engagement with the reproducer for lifting the same from a played record, means for holding said member in elevated position, electro-magnetic means for releasing said holding means, a time element in circuit with said electro-magnetic means, and means for operating said time element to close the circuit to said electro-magnetic means, substantially as described. 70
35. An attachment for phonographs, comprising a reproducer lifting member normally out of engagement with the reproducer, a cam for lifting said member into engagement with the reproducer for lifting the same from a played record, means for holding said member in elevated position, electro-magnetic means for releasing said holding means, a time element in circuit with said electro-magnetic means, and means for operating said time element to close the circuit to said electro-magnetic means, substantially as described. 75
36. In a phonograph, a record table, a drive spindle therefor, a cam on said spindle having an operative surface extending only part way around said spindle, a reproducer, a reproducer lifting arm having a portion adapted to engage said cam and another portion adapted to engage the reproducer, said cam engaging portion being normally out of engagement with the cam, and means for bringing said cam engaging portion into engagement with the cam upon the completion of the playing of a record on said table for shifting the reproducer, substantially as described. 80
37. In a phonograph, a record table, a drive spindle therefor, a cam on said spindle having an operative surface extending only part way around said spindle, a reproducer, a reproducer lifting arm having a portion adapted to engage said cam and another portion adapted to engage the reproducer, said cam engaging portion being normally out of engagement with the cam, and means for bringing said cam engaging portion into engagement with the cam upon the completion of the playing of a record on said table for shifting the reproducer to playing position during a single revolution of said spindle, substantially as described. 85
38. In a phonograph, a record table, a drive spindle therefor, a cam on said spindle having an operative surface extending only part way around said spindle, a reproducer, a reproducer lifting arm having a portion adapted to engage said cam and another portion adapted to engage the reproducer, said cam engaging portion being normally out of engagement with the cam, means for bringing said cam engaging portion into engagement with the cam upon the comple- 90

tion of the playing of a record on said table for shifting the reproducer, and means for holding said reproducer in shifted position, substantially as described.

5 39. In a phonograph, a record table, a reproducer cooperating therewith, a cam, a reproducer lifting arm having a cam engaging portion and a reproducer engaging portion, means normally urging said

cam engaging portion into engagement with the cam, holding means for normally rendering said means ineffective, and adjustable means cooperating with the reproducer for releasing said holding means, substantially as described.

In testimony whereof, I have hereunto set my hand.

EDGAR E. BROSIUS.
